UNITED STATES PATENT OFFICE

JAMES HUBER, OF PHILADELPHIA, PENNSYLVANIA, ASSIGNOR TO VICKERS LTD
OF WESTMINSTER, LONDON, ENGLAND.

SUBMARINE MINE.

1,314,656.

Specification of Letters Patent. Patented Sept. 2,

Application filed July 10, 1917. Serial No. 179,735.

To all whom it may concern:

Be it known that I, JAMES HUBER, a citizen of Switzerland, and residing at Philadelphia, in the county of Philadelphia and the 5 State of Pennsylvania, have invented certain new and useful Improvements in Submarine Mines; and I do hereby declare the following to be a full, clear, and exact description of the invention, such as will enable others 10 skilled in the art to which it appertains to make and use the same.

This invention relates to a submarine mine.

The object of the invention resides in the 15 provision of means for securing the mine and anchor together and for securing the sounding ball to the anchor, which means is operable under the influence of the buoyancy of the mine to release the sounding ball and 20 subsequently to release the anchor from the mine.

The further object of the invention resides in the provision of means for preventing the release of the anchor from the mine or the 25 sounding ball from the anchor until the mine dips over the curves of the launching rails, which means is at this time automatically rendered inoperative.

Referring to the drawings:—

30 Figure 1 is a fragmental view of the mine showing the invention applied thereto.

Fig. 2 is an enlarged elevation of the invention, and

Fig. 3 is a sectional view of means for 35 securing the mine and anchor together.

In the drawing, a portion of a mine 1 and a portion of an anchor 2 are disclosed.

The means for securing the mine and anchor together is somewhat similar to that 40 illustrated and described in my co-pending application, Serial No. 173,182, filed June 6, 1917. This means includes a cylinder 3 which is pivoted at 4 between ears 5, the latter being formed on a plate 6 which is 45 secured to the side of the anchor by suitable means, such as bolts 7. The upper end of this cylinder 3 is closed by a socket member 8, which is provided with a socket 9 in which a connecting element 10 operates. 50 This connecting element is, at one end, connected to the turnbuckle 11 of the mine cable and is provided with a pair of legs 12 which extend into the socket 9 but may be withdrawn therefrom, as will later appear. 55 These legs are provided at their lower ends

with toe portions 13 which engage the end of a piston rod 14, which carries the lower end a piston 15, the latter being in the cylinder 3. The connecting member 10 is held in engagement with the rod 14 during the initial movement of the piston in the cylinder but is permitted to disengage the rod after the legs 12 pass out of the socket 9, in a similar to that described in the abandoned co-pending application. The movement of the piston in the cylinder 3 is governed by fluid pressure within the cylinder. Pivoted at 16 to the lower end of the plate 6 is a pelican hook 17 adapted to support the sounding ball of the anchor. The upper end of this hook is arranged to bear against the end of a slide 19 at 20, which slide is guided between the ears 5 on the plate 6. The slide 19 is formed at the upper end of the ears 21 formed at the upper end of the plate, the slide being guided by rods carried by the respective ears. The end of the slide is provided with a finger 23 which projects a recess 24 between the legs 12 of the connecting member 10, the recess being above the uppermost end of the slide when the legs of the connecting member 10 are within the socket. When this is free to move upwardly, the buoyancy of the mine will cause such movement at the same time cause the legs 12 of the connecting member 10 to move out of the socket 9. The continuing relative movement of the mine and anchor will cause the legs 12 to separate and permit the finger 23 to pass between and from the lower end of the slide 19 same so that it will be entirely disengaged from the slide and this disengagement will be entirely disengaged from the anchor permitted the mine entirely. Of course, upon the initial upward movement of the slide 19 before the connecting member 10 leaves the socket 9, the pelican hook 17 is disengaged from the slide and this disengagement permits the hook to drop about it whereby the sounding ball 18 will be released. The release of the sounding ball 18 the entire disengagement of the mine from the anchor, will permit the sounding ball 18 to drop into its operative position so that thereafter be effective to accomplish its function.

It is, of course, desirable to prevent the release of the connecting member

to the dipping of the mine over the curved ends of the launching rails, so that the mine and anchor will be locked together and the sounding ball will be locked to the anchor. 5 To this end, I have provided a latch 25 which, in the form of the invention illustrated, is pivoted at 26 to the upper end of the pelican hook 17 and is located between the furcations of the same but which may be pivoted to the anchor or by an element carried by the same. In the form illustrated, the latch 25 is free to move between the furcations of the hook 17 to a limited extent only, because of the presence of shoulders 10 27, with which the lower end of the latch engages and which shoulders are disclosed clearly in Fig. 2. The bill 28 of the latch is adapted to engage the projection 29 on the lower end of the slide 19. This bill is 15 normally pressed into engagement with the projection 29 by a spring 30, which as illustrated, is secured to the plate 6 and bears against the upper end of the latch member 25 above its pivoted point. It is to be understood, that the inside edge of the pelican hook 17 is formed with a depression 31, in which the ring 32 of the sounding ball 18 is located prior to the launching of the mine. The location of the ring 32 in this depression 20 31 makes it impossible for the ring to engage the lower end of the latch member 25 and consequently, the accidental disengagement of the latch member from the slide 19 will be obviated. 35 It is to be understood that when the mine dips over the curves of the launching rails, that the sounding ball 18 will swing outwardly from the anchor and will engage the lower end of the latch 25. The weight of the sounding ball will cause the movement of the latch member 25 about its pivot 26 against the action of the spring 30, so that the bill of the latch will be disengaged from the projection 29 on the slide 19, and 40 the slide will be free to move when the mine strikes the water. As above described, when the mine strikes the water, the buoyancy of the mine will cause the slide 19 to move upwardly so that the pelican hook 17 will be 45 disengaged and the sounding ball will drop to its operative position and so that subsequently, the finger 23 of the slide 19 will be disengaged from the connecting member 10 and the anchor and mine consequently free to separate entirely. 50 It is of course to be understood, that the exact construction of the connection between the anchor and the mine is not at all essential, for the construction illustrated in 55 the drawing, of course, may be used, or that illustrated in the above referred to co-pending application may be modified to accommodate the finger 23 and may be used. It is only essential that this connection between the mine and anchor be a sep- 60 65

arable connection, the parts of separate under the action of the of the mine and only after the ball has been released.

What I claim is:—

1. The combination with a mine, its anchor and its soundi means for attaching the ball to means for securing the attachin operative position and means for securing means.

2. The combination with a mine, its anchor and its soundi means for attaching the ball to means for securing the attachin operative position and means for last mentioned means, the ball able, when the mine is tipped on rails, to release the last menti

3. The combination with a mine, its anchor and its soundi means for securing the anchor together including a pair of se ments, means for attaching th ball to the anchor, means opera of said separable elements for the attaching means, and mea venting the operation of the last means until the mine is tipped.

4. The combination with a mine, its anchor and its soundi means for securing the anchor together including a pair of se ments, means for attaching th ball to the anchor, means opera of said separable elements for the attaching means and means ling the last mentioned means.

5. The combination with a mine, its anchor and its soundi means for securing the anchor together including a pair of se ments, means for attaching th ball to the anchor, means opera of said separable elements for the attaching means, and mea matically controlling the opera last mentioned means.

6. The combination with a mine, its anchor and its soundi means for detachably securing and mine together, means for the sounding ball on the anchor for preventing the release of from the mine until the sound released from the anchor.

7. The combination with a mine, its anchor and its soundi means for detachably securing and mine together, means for the sounding ball on the anchor operated by the sounding ball: ing the release of the anchor fr until the sounding ball is releas anchor.

8. The combination with a submarine mine, its anchor and its sounding ball, of means for securing the anchor and mine together including a pair of separable elements, an element pivoted on the anchor for supporting the sounding ball, means connected with one of said separable elements and engaging said pivoted element to prevent the movement of the latter to release the ball and means for engaging the last mentioned means to prevent the separation of the separable elements until the mine is tipped.

9. The combination with a submarine mine, its anchor and its sounding ball, of

means for securing the anchor and mine together, including a pair of separable elements, an element pivoted on the anchor for supporting the sounding ball, means connected with one of said separable elements and engaging said pivoted element to prevent the movement of the latter to release the ball and means controlled by the sounding ball for engaging the last mentioned means to prevent the separation of the separable elements until the mine is tipped. 20

In testimony whereof I affix my signature.

JAMES HUBER.
